(No Model.)

W. L. VOELKER.

APPARATUS FOR MANUFACTURING INCANDESCENT LAMPS AND CARBONS.

No. 251,749.

Patented Jan. 3, 1882.

UNITED STATES PATENT OFFICE.

WILLIAM L. VOELKER, OF MORTON, PENNSYLVANIA.

APPARATUS FOR MANUFACTURING INCANDESCENT LAMPS AND CARBONS.

SPECIFICATION forming part of Letters Patent No. 251,749, dated January 3, 1882.

Application filed August 5, 1881. (No model.)

To all whom it may concern:

Be it known that I, WILLIAM L. VOELKER, of Morton, in the county of Delaware and State of Pennsylvania, have invented certain new and useful Improvements in Apparatus for Manufacturing and Testing Incandescent Electric Lamps and Carbons, of which the following is a full, clear, and exact description, reference being had to the accompanying drawing and the letters marked thereon.

My invention relates especially to apparatus used in the manufacture of incandescent electric lamps, and has for its object the production of a device whereby the material of which the filaments to be used in the lamp may be carbonized, nitrogen gas for testing the carbons may be generated, the glass bulbs of the lamp may be annealed, and the completed lamp and carbon thoroughly dried before sealing; and my invention involves certain novel and useful combinations or arrangements of parts and peculiarities of construction and operation, all of which will be hereinafter first fully described, and then pointed out in the claims.

The drawing herewith presented represents a sectional view of my improved apparatus, indicating the location and arrangement of the various parts.

30 A is the outside or main wall of a furnace constructed of iron, fire-brick, or any other preferred material.

B is a fire-pot, so arranged and constructed as to supply the requisite degree of heat.

35 C is an air-supply pipe, connected with any style of fan or blower.

A' is an oven, located directly above the fire-pot, wherein the glass bulbs D are placed after forming for the purpose of annealing. A² is 40 also an oven placed above oven A'. It being farther removed from the fire-pot does not maintain as high a degree of heat as A'. In this upper oven are placed suitable conductors, aa, for connection with a dynamo-machine.

45 The heat and products of combustion pass from the fire-pot up upon each side of the ovens and out through flue B' at the top of the structure, said flue having connection with a suitable chimney.

50 C' is a pipe leading from the air-supply pipe C to pipe C², passing through the fire-pot.

c² is a suitable valve for regulating the flow of the air through pipe C'.

Pipe C², when the device is in operation, contains copper filings c.

55 C³ is a tube communicating with a series of flasks, E, containing sulphuric acid, and from said flasks communication is had with flasks E², containing hydrate of potassium, the latter flasks communicating with tube E³, containing 60 chloride of calcium. F is a receiver, connected with pipe E³ by means of tube F'.

G is a suitable muffle, containing the filaments to be carbonized.

65 G' is a carbon, with its proper connections for use in a lamp, placed in receiver F; and G² are lamps ready to seal, connected up with wires aa in oven A².

H is a dynamo-machine, and H' is a resistance-coil.

70 H² H³ are resistance-circuits for regulating the strength of the current from the dynamo.

75 My device for the manufacture of the nitrogen to be used in testing the carbons, as above explained, needs no further notice, the same being well known and understood by all chemists.

When the filaments of carbon have been prepared in oven A' they are united to their connections and placed in the receiver F and in the dynamo circuit, as shown. It is often the 80 case that there will exist in a filament a flaw or imperfection imperceptible to the eye, and which could not be discovered until the completed lamp was put in use, when, if such flaw existed, it would render the lamp worthless, 85 for, when heated to incandescence, that being the point of greatest resistance, the carbon would heat unequally and soon break. This difficulty I overcome by testing the carbons in F by passing a current from the dynamo there-through before sealing up permanently in the lamp-bulb, and if any carbon is found imperfect it may be discarded with very little loss of time or useless expense.

90 It is a well-known fact that carbon, particularly in the form of charcoal, or that manufactured from the coke of gas-retorts, has the property of absorbing moisture in a very high degree, which, if made into a filament for use in an incandescent lamp and placed in the bulb 95 and heat applied to the exterior of the lamp, would not thereby be expelled; but by use of

my improved device the lamps may be completed, except sealing up, and placed in oven A², as shown. By passing a current from the dynamo properly regulated by resistance through the carbons and maintaining them at a temperature a little below red heat all the moisture will be expelled. The glass globes being kept hot by the fire-pot, there is no danger of condensation taking place therein. After remaining a sufficient time in oven A² the lamps are removed to the air-pump and sealed in the manner well known and understood by those skilled in the art to which my invention relates. If the moisture were not expelled from the carbon, as above explained, and the lamp after being exhausted were used for illuminating purposes, as soon as the electric current heated the filament of carbon therein to a white heat, any moisture would be decomposed into gases highly destructive to the same.

Having now fully described my invention, what I claim as new therein, and desire to secure by Letters Patent, is—

1. The herein-described device for manufacturing and testing incandescent electric lamps, consisting of a furnace or fire-pot supplied with an air-blast, the annealing-oven and the drying-oven located above said fire-pot, and the nitrogen-generator in said fire-pot, the whole

combined and arranged to operate substantially as set forth. 30

2. The herein-described method of expelling the moisture from the glass bulbs of incandescent electric lamps and their inclosed carbon by subjecting said lamps before sealing to heat 35 of the requisite temperature and at the same time passing an electric current therethrough, substantially as shown and described.

3. In a device for manufacturing and testing incandescent lamps and carbons, the fire-pot 40 B, blast-pipe C, pipes C' and C², annealing-oven A', and drying-oven A², the whole combined and arranged to operate substantially as shown and described.

4. In a device for manufacturing and test 45- ing incandescent electric lamps and carbons, the combination, with the oven A², heated by fire-pot B, of the conductors a a, having connection with a dynamo-machine, substantially as shown and described.

In testimony that I claim the foregoing I have hereunto set my hand in the presence of two witnesses.

WILLIAM L. VOELKER.
